UNITED STATES PATENT OFFICE.

MARTHA ST. CLAIR WINGERT, OF WHITTIER, CALIFORNIA.

DESIGN FOR A DOLL.

52,421.

Specification for Design. Patented Sept. 10, 1918.

Application filed April 9, 1918. Serial No. 227,578. Term of patent 14 years.

To all whom it may concern:

Be it known that I, MARTHA ST. CLAIR WINGERT, a citizen of the United States, residing at Whittier, in the county of Los Angeles and State of California, have invented a new, original, and ornamental Design for Dolls, of which the following is a specification, reference being had to the accompanying drawing, forming a part thereof.

Fig. 2 is a rear elevation of the doll shown in Fig. 1.

I claim:

The ornamental design for a doll as shown.

MARTHA ST. CLAIR WINGERT.
